CLAIM

The ornamental design for a spacer for shut-off valve, as shown and described.

DESCRIPTION

FIG. 1 is a front, top and right side perspective view of a spacer for shut-off valve showing our new design;

FIG. 2 is a rear, top and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a cross-sectional view taken along line 8-8 in FIG. 7 showing the claimed area;

FIG. 9 is a cross-sectional view taken along line 9-9 in FIG. 7 showing the claimed area;

FIG. 10 is a cross-sectional view taken along line 10-10 in FIG. 7 showing the claimed area;

FIG. 11 is a cross-sectional view taken along line 11-11 in FIG. 7 showing the claimed area;

FIG. 12 is a rear, top and right side perspective view thereof with an operational member being pushed;

FIG. 13 is a first reference view of usage thereof;

FIG. 14 is a second reference view of usage thereof; and,

FIG. 15 is a third reference view of usage thereof.

The evenly-spaced broken lines illustrate portions of the spacer for shut-off valve that form no part of the claimed design. The dash-dotted broken lines denote the boundary of the claim and form no part of the claimed design.
